(57) **CLAIM**

The ornamental design for the coupling insert, as shown and described.

DESCRIPTION

FIG. 1 is a first top perspective view of the coupling insert.

FIG. 2 is a second top perspective view thereof.

FIG. 3 is a top view thereof.

FIG. 4 is a side view thereof.

FIG. 5 is an end view thereof; and,

FIG. 6 is an opposite end view thereof.

The bottom and other side are identical to the top and side shown in FIGS. 3 and 4, respectively. The broken line showing aspects of the coupling insert is for the purpose of illustrating environmental structure and forms no part of the claimed design.
